UNITED STATES PATENT OFFICE.

GEORGE ALBERT LETTER, OF CHICAGO, ILLINOIS.

SOCKET FOR TWIST-DRILLS.

SPECIFICATION forming part of Letters Patent No. 321,615, dated July 7, 1885.

Application filed April 4, 1885. (No model.)

To all whom it may concern:

Be it known that I, GEORGE A. LETTER, a citizen of the United States, residing at Chicago, in the county of Cook and State of Illinois, have invented a new and useful Improvement in the Sockets for Holding Twist-Drills, of which the following is a specification.

The object of my invention is to provide a fastening for drills in drill-sockets when the keeper is broken off the drill. I attain this object by the mechanism illustrated in the accompanying drawings, in which—

Figure 1 is an elevation. Fig. 2 is a vertical section of Fig. 1, taken through $x x$. Fig. 3 is a cross-section of Fig. 1, showing a modification of my invention.

Fig. 1 shows a drill-socket with a drill inserted therein. In the lower part of the drill-socket I mill out a space sufficiently long and wide to admit a key, c . This opening passes through the socket to the hole occupied by the drill B . The key is held in position by a pin, e , as shown in the drawings, and it passes through the solid portion of the socket and forms a pivoting-point for the key. The hole f in the key is made as shown in Fig. 2. This allows the key to fall into position at both ends alike. The lower end of the key c is rounded on the inner edge, so that when the drill enters the socket and strikes the end of the key it will pass under the key and allow it to go to its place in the socket.

To prevent the lower end of the key from passing beyond the outer surface of the socket, I taper off the lower end of the key to an angle to the axis of the socket shown at g in Fig.

2. To accomplish this I drill a tapering hole in the bottom of the socket and put in a metal pin, as shown at g , Fig. 2. The key as it is pressed outward strikes against this pin and

is prevented from getting out of the socket. The lower end of the material of the socket at this point might be filed into a taper; but I prefer the pin inserted as described. The drill has a key-seat milled in it, (shown at h ,) 45 into which the key c drops when it is inserted, and the drill is thereby held from turning when the keeper or square portion at the upper end of the drill is broken off, which often happens.

The object of pivoting the key c , as shown, is to allow it to move back, if, at any time, the operator should put the drill into the socket in such a manner that the key does not immediately enter the seat h . In such case the 55 key moves out of the way, and as soon as the drill is operated it turns around in the socket until the seat reaches the key, when it drops into it and is held fast therein. If the key has no seat, it is pushed out of the way, and the 60 drill is held by the keeper unless it is broken off, when it is necessary to key-seat the drill or put on a new keeper. The former saves time and expense.

Fig. 3 shows a modification of my invention. 65 The key is inserted in the socket and a set-screw jams it tight onto the drill. The key has small teeth in its side next to the drill. The drill at this point may be flattened or round, as shown in the drawings.

What I claim, and desire to secure by Letters Patent, is—

A drill-socket, A , having a movable key, c , pivoted therein for the purpose of holding the drill when the keeper is broken off, substantially as described.

GEORGE ALBERT LETTER.
